UNITED STATES PATENT OFFICE.

WILLIAM H. CATER, OF CHICAGO, ILLINOIS.

WELL-SCREEN.

1,342,986.

Specification of Letters Patent. Patented June 8, 1920.

Application filed July 28, 1919. Serial No. 313,723.

To all whom it may concern:

Be it known that I, WILLIAM H. CATER, a citizen of the United States, residing at Chicago, in the county of Cook and State of Illinois, have invented certain new and useful Improvements in Well-Screens, of which the following is a specification.

My invention pertains to screens or strainers of various kinds but more particularly concerns features of novelty and improvement, both from structural and functional standpoints, in well-screens adapted to permit the passage of water therethrough but to hold back sand, dirt, gravel and the like. One leading object of the invention is the provision of a tubular screen or strainer of substantial size and strength with a relatively small or fine mesh. Holes of the small caliber required for a screen or filter of the fine mesh desired cannot satisfactorily be punched in sheets of metal of a thickness sufficient to give the tube or pipe adequate strength. A punch small enough to produce the minute holes desired would have inadequate strength to perform the punching or metal removing operation without breaking. Accordingly, it becomes necessary to use some other expedient to produce the desired result.

In accordance with the principles of this invention in its preferred embodiment a long sheet-metal strip is punched to produce round holes of a size permitted by the thickness or gage of metal needed to produce a tube of the required strength such round holes are too large to perform by themselves alone the screening or filtering operation. Such sheet-metal strip is wound up spirally with its longitudinal marginal or edge portions overlapped and riveted or otherwise secured together, thereby forming a hollow, cylindrical, perforated tube or pipe with an exposed, outer, spiral shoulder or ledge produced by the edge of the metal sheet. This spiral tube is provided with an outer shell comprising a similarly-arranged, spiral, metal sheet encircling the inner one and bearing at one edge on the spiral or helical shoulder specified, its other longitudinal border or margin being riveted, soldered, or otherwise fastened to the inner or underlying thicker metal sheet. Such outer spiral sheet has elongated or narrow rectangular openings or slots of finer mesh than the round holes of the inner sheet and more or less in register

therewith, the apertures of the surrounding or encircling sheet having their longer axes or dimensions substantially-parallel to the axis of the tube or pipe to facilitate cleaning and to prevent clogging, at least in some degree.

When a screen or strainer of still finer mesh is wanted a spirally-disposed wire-cloth or fine-mesh screen (copper or bronze for instance) is interposed between the two apertured or perforated metal sheets, whereby the screen as a whole is composed of these three superposed spirally-arranged screen members or elements, all of different mesh, the finer one being between, held in place by, and protected from injury or damage by the other two.

In order that those skilled in this art may have a full and complete understanding of this invention and its various benefits and advantages, I have illustrated in the accompanying drawing, forming a part of this specification, a preferred and desirable embodiment of the invention, the single view of the drawing showing fragmentarily a section of the improved screen or strainer with the parts broken away to more clearly illustrate the construction.

As is clearly depicted the strainer, screen, or filter comprises a hollow cylindrical tube or casing composed primarily of a relatively-long sheet of metal 10, provided with a plurality of round perforations 11, bent or shaped into spiral or helical form with its longitudinal margins or borders overlapped and secured together as by a spiral row of rivets 12.

The lower edge portion of the sheet at such spiral joint fits inside of the adjacent upper edge portion of another section of the sheet, whereby the tube or pipe internally presents no obstruction to the downward insertion of any member of substantially the diameter of the inner caliber of the pipe.

Such helical joint provides an external spiral shoulder 13 formed by the exposed edge of the metal sheet which is taken advantage of in properly positioning and holding in place the outer, perforated, metal sheet.

Surrounding this supporting tube or shell and bearing against its outer face and of a width to cover its numerous holes is a spirally-arranged wire-cloth screen 14, desirably of copper, of the required mesh for the screen as a whole.

Outside of this is another spirally-disposed sheet of metal 15 thinner than the inner sheet 10 and hence capable of having smaller holes or apertures 16 therethrough, 5 such holes being in the form of elongated slots whose axes in the finished tube are substantially parallel to its axis. Such metal sheet 15 preferably bears at one edge against, and is protected by, the spiral shoulder 13 of the thicker metal sheet 10 and its other or upper border or margin is fastened to the underlying sheet 10 by a row of rivets 17 or by solder, welding, or otherwise. 10

It will be perceived that the strainer or 15 screen as a whole comprises a plurality of spirally-arranged, superposed, reticulated or foraminous members or sheets which unitedly or conjointly form a structure of suitable and sufficient strength and of relatively fine mesh or gage. In some cases 20 where a coarser mesh structure is required, the intermediate wire-cloth screen 14 may be omitted, the tube or pipe then comprising only the two perforated metal sheets with 25 apertures of different sizes and of metal of different gages.

It will be readily understood that this 30 invention is not limited and restricted to any exact measurements of the parts but merely by way of example I might mention that for a pipe or tube twenty inches in diameter the width of the metal strip 10 could conveniently be fifteen inches, and provided with round holes of approximately a half 35 inch diameter across about ten inches of its width. The outer strip 15 would, of course, be made somewhat narrower than the strip 10 and if composed of eighteen gage metal its holes might desirably be one-half inch 40 long and one thirty-second inch wide with approximately 45% of the metal cut away. The wire-cloth screen 14 could be of any suitable finer mesh or gage and of course would be of a width to cover the holes or 45 perforations of the two spiral metal sheets between which it is held.

In actual practice tubes of standard and 50 ordinary size are made up of the single sheet 10 and kept in stock. Upon order, such main supporting tubes are supplemented by or fitted with the spiral perforated sheet 15 with holes of the required size, and if a still finer mesh is required a sheet 14 of the wire-cloth screen is interposed between 55 and held in position by the other two.

The spiral or helical sheet 10, of course, 60 constitutes the main body of the tube or pipe and is made of metal of sufficient thickness to withstand the usual strains and stresses. The smallness of the sizes of the holes which 65 may be punched in such sheet is strictly limited as explained above and when a finer mesh of tube is needed these holes must be supplemented with others of smaller size. 65 By arranging the slots in the outer metal

sheet vertically the water in passing therethrough tends to wash or flush out any dirt finding lodgment therein and consequently the strainer or screen is in large measure self cleaning.

By those skilled in this art it will be appreciated that the invention is not limited and restricted to the precise and exact features of structure illustrated and described and that many minor mechanical changes 75 may be incorporated in the construction without departure from the substance and essence of the invention and without the sacrifice of any of its substantial benefits and advantages. 80

I claim:

1. A well-screen of the character described, comprising in combination a tube composed of a sheet of metal with a smooth outer surface bent to spiral form having a 85 series of perforations intermediate its edges and its one longitudinal marginal portion outwardly overlapping the opposite longitudinal marginal portion of the sheet and secured thereto, the edge of the outer overlapping part forming an exterior upwardly-facing spiral shoulder, and a second sheet of metal bent into spiral form around said first sheet and secured thereto and having apertures therethrough of a size different from 90 those of said first sheet, substantially as described.

2. A well-screen of the character described, comprising in combination a tube composed of a sheet of metal with a smooth 100 outer surface bent into spiral form having a series of perforations intermediate its edges and its one longitudinal marginal portion outwardly overlapping the opposite longitudinal marginal portion of the sheet and 105 secured thereto, the edge of the outer overlapping part forming an exterior upwardly-facing spiral shoulder, and a second thinner sheet of metal bent into spiral form around said first sheet and secured thereto and having 110 apertures therethrough of a size and shape different from those of said first sheet, substantially as described.

3. A well-screen of the character described, comprising in combination a tube 115 composed of a sheet of metal with a smooth outer surface bent into spiral form having a series of round perforations intermediate its edges and its one longitudinal marginal portion outwardly overlapping the opposite 120 longitudinal marginal portion of the sheet and secured thereto, the edge of the outer overlapping part forming an exterior upwardly-facing spiral shoulder, and a second thinner sheet of metal bent into spiral form around 125 and secured to said first sheet and having elongated holes therethrough with their longer dimensions disposed substantially parallel to the axis of the tube, substantially as described. 130

4. A well-screen of the character described, comprising in combination a tube composed of a sheet of metal with a smooth outer surface bent into spiral form having a series of perforations therethrough intermediate its edges and its one longitudinal marginal portion outwardly overlapping the opposite longitudinal marginal portion 65 of the sheet and secured thereto, the edge of the outer overlapping part forming by its exposed edge an exterior upwardly-facing spiral shoulder, a second sheet of metal bent into spiral form around said first sheet and secured thereto and having apertures therethrough of a size different from those of said first sheet, and a spirally-disposed wire-cloth screen between said perforated metal sheets, substantially as described. 70 75
5. A well-screen of the character described, comprising in combination a tube formed of a sheet of metal with a smooth outer surface bent to spiral form having a series of perforations therethrough intermediate its edges and its one longitudinal 80 marginal portion outwardly overlapping the opposite longitudinal marginal portion of the sheet and secured thereto, the edge of the outer overlapping part forming by its exposed edge an exterior upwardly-facing spiral shoulder, and a second thinner sheet of metal bent into spiral form around and secured to said first sheet and having its lower edge substantially in contact with and protected by said spiral shoulder, said second sheet having 85 apertures therethrough of a size different from those of said first sheet, and a spirally-disposed wire-cloth screen between said perforated metal sheets, substantially as described. 90 95
6. A well-screen of the character described, comprising in combination a tube composed of a sheet of metal with a smooth outer surface bent into spiral form having a series of round perforations therethrough intermediate its edges and its one longitudinal marginal portion outwardly overlapping the opposite longitudinal marginal portion of the sheet and secured thereto, the edge of the outer overlapping part forming by its exposed edge an exterior upwardly-facing spiral shoulder, and a second thinner 100 sheet of metal bent to spiral form around and secured to said first sheet and having 105 its lower edge substantially in contact with and protected by said spiral shoulder, said second sheet having elongated holes therethrough with their longer dimensions disposed substantially parallel to the axis of the tube, substantially as described. 110 115
7. A well-screen of the character described, comprising in combination a tube composed of a sheet of metal with a smooth 120

WILLIAM H. CATER.
